TUBE END DEFORMING MACHINE WITH
AUTOMATIC TUBE CLAMPING MEANS

Arthur L. Parker, Cleveland, Ohio, assignor to
The Parker Appliance Company, Cleveland,
Ohio, a corporation of Ohio

Application December 26, 1944, Serial No. 569,763

5 Claims. (Cl. 153—79)

1

The present invention relates to tube machines and more particularly to hydraulically operated tube end deforming machines.

The primary object of the invention is to provide a machine capable of flaring or otherwise deforming the end of a tube of a relatively large diameter.

A further object of the invention is to provide a tube end deforming machine wherein means have been provided for firmly gripping the tube end so as to prevent slipping thereof during the deforming operation.

A still further object of the invention is to provide a tube end deforming machine of the above character wherein there is employed a pair of pistons operating in individual cylinders, one of the pistons actuating the tube clamping means and the other piston actuating the tube deforming means.

The above and other objects of the invention will in part be obvious and will in part be hereinafter more fully pointed out.

In the drawings.

Figure 1 is a rear end elevational view of a tube deforming machine embodying the features of the present invention.

Figure 2 is a vertical sectional view taken substantially on line 2—2 of Figure 1.

Figure 3 is a view in plan of the left hand portion of the machine and in section through the frame-work of the right hand portion of the machine, said section being taken in a horizontal plane diametrically of the cylinders.

Figure 4 is a detail sectional view of the tube end clamping means in relaxed position.

Figure 5 is an end view thereof.

In the copending application of Henry E. Hull et al., filed December 26, 1944, Serial No. 569,751, issued as Patent No. 2,478,102, August 2, 1949, for a Tube end deforming machine, there is disclosed and claimed a portion of the apparatus shown in the present application. The copending application relates to a tube end deforming machine having means for clamping the end of the tube to be deformed and hydraulic means associated therewith for actuating the clamping means. Said application further discloses a tube end deforming element which is actuated by hydraulic means associated therewith. Both hydraulic means include a pair of pistons operable in individual cylinders, one of the pistons actuating the tube clamping means and the other piston actuating the tube deforming means.

The present application corresponds to the above mentioned copending application in that

there is employed a pair of pistons operating in individual cylinders for actuating the tube clamping means and tube deforming means respectively. The present invention differs from the copending application in the specific means provided for firmly gripping the tube end during the deforming operation, and is intended primarily for flaring or otherwise deforming tubes of three-fourths inch diameter and larger. These larger tubes are difficult to flare or deform and require a very firm grip of the end portion which will not slip during the deforming operation.

Referring to the drawings for more detailed description thereof, and particularly Figures 1, 2 and 3, the machine is shown to include a rectangular shaped base plate 1 on which is mounted spaced upright members 2 and 3, said members being mounted at each end of the base plate and fixedly secured thereto in any desired manner. Mounted between the uprights 2 and 3 is a pair of cylinders 4 and 5 maintained in spaced relation by means of the spacer member 6. The cylinder 4 carries a piston 7 and the cylinder 5 carries a piston 8, said pistons being suitably packed by means 9 within the cylinders. The uprights 2 and 3, cylinders 4 and 5, and spacer member 6 are linked together by means of tie bolts or the like 10, there being preferably provided eight of these tie bolts as shown in Figure 1 of the drawings.

The front upright member 2 is formed with an annular recess 11 at its outer end for receiving a cam ring 12, and chuck 13, the chuck being held against longitudinal movement by means of the plate 14 which plate is held in position by a series of threaded studs 15 provided with scalloped thumb nuts 16. The recess 11 is of a depth substantially equal to the length of the chuck 13, and thus said chuck is held against longitudinal movement between said plate and the rear wall 17 of the recess 11. As will hereinafter appear, the chuck 13 is adapted to grip the end of the tube 18 which is to be deformed and the plate 14 is provided with a central bore 19 through which the tube end is inserted.

The chuck is of the type shown in the before mentioned copending application and comprises four tapered segmental members 20, see Figs. 5 and 6, the outer periphery of which is formed with an annular groove 21 for receiving a snap ring 22. This snap ring maintains the segments in unitary relation at all times. The chuck further includes coil springs 23 mounted in drilled holes in each segment so that the segments will be urged out

3
of tube gripping engagement for permitting the completed tube to be readily removed and a new one inserted therefor. The segments of the collar are urged into tube gripping engagement by means of the cam ring 12, it being understood that as said cam ring moves out of contact with the chuck, the coil springs 23 will cause the segments to spring away from tube gripping engagement.

The chuck 13 contacts the outer periphery of the end of the tube 18 when the end thereof is to be deformed and in accordance with the present invention means have been provided which cooperate with the outer chuck 13 for contacting the inner periphery of said tube end so as to provide a very firm grip on the tube end to prevent slipping thereof during the flaring operation. Referring to Figures 2 and 4 of the drawings, it will be noted that this means comprises an internal chuck generally designated by the reference numeral 24. The internal chuck 24 is made up of a series of segments 25, the outer periphery 26 being substantially cylindrical shaped so as to conform to the inner surface of the tube 18. The segments 25 are maintained in assembled relation by means of a snap ring 27 retained within an annular groove 28, and said segments when assembled present a substantially cylindrical shaped member having a tapered central bore 29. An expander rod 30 is slidably mounted within the bore 29, said rod being provided with an enlarged tapered end 31, the outer periphery of which generally conforms to the tapered bore 29. As will hereinafter appear, the expander rod 30 is moved axially relative to the tube 18 for causing the internal chuck segments 25 to expand outwardly and thereby expand the tube into engagement with the outer chuck 13. The internal chuck segments 25 are formed with an annular shoulder 32 adapted to receive a spring ring 33, said ring being also engageable in back of an annular shoulder 34 formed on a tubular rod 35. Provision of the spring ring 33 further maintains the chuck segments 25 in a substantially unitary relation, expansion of said segments occurring at the outer end thereof, wherein is positioned the snap ring 27 within the annular groove 28. The cam ring 12, which is mounted within the annular recess 11, is formed with a bore 36 tapering downwardly and outwardly and generally conforming to the shape of the outer periphery of the chuck 13. With the cam ring 12 in the position shown in Figure 2 of the drawings, the outer chuck segments 20 are actuated radially inward to grip the tube 18 for the end deforming operation. The cam ring 12 is actuated by the piston 8 in the rear cylinder 5 and is connected to said piston by means of four draw bolts 37. The forward end of the draw bolts are provided with knurled nuts 38 which extend through the plate 14 and are held against the ring 12. The other end of the draw bolts 37 screwthreadedly engage a plate 39 which plate is mounted on the reduced end 40 of the piston 8, being locked thereon by means of the lock nut 41.

The piston 8 is formed with a central bore 42 throughout its length and mounted within said bore is a guide sleeve 43, one end of which terminates within the spacer members 6 as indicated at 44. A collar 45 is formed on the guide sleeve 43 and is maintained in abutting relation with the spacer member for limiting its movement in one direction. The piston 8 is suitably packed by means 46 on the guide sleeve 43. Thus it will be seen that as the piston 8 moves toward the

5 right or left as viewed in Figure 2, it will be guided on the sleeve 43 and will carry with it the plate 39, draw bolts 37, and cam ring 12 since these parts are all united. Movement of the cam ring 12 to the left as viewed in Figure 2 permits the outer chuck segments 20 to be urged away from tube gripping engagement by means of the spring 23.

10 The piston 8 is movable toward the left as viewed in Figure 2 for deforming the end 47 of the tube 18. This piston 8 is formed with a central bore in which is received the tubular rod 35, which rod carries the ring 33 for uniting the inner end of the internal chuck segments 25, as before described. One end 49 of the tubular rod 35 extends into the spacer member 6 and is held in abutting relation with the end 44 of the sleeve 43. The rod 35 and sleeve 43 have a central bore of the same internal diameter through 15 which extends the expander rod 30 which is adapted to be actuated by the piston 8 and is therefore adjustably connected to the end 40 of said piston by the nut 50. Referring to Figure 2 of the drawing, it will be noted that the expander rod 30 extends through the plate 39 and lock nut 41, being adjustably connected to the latter by the means 50 which in this instance comprises a lock nut. Thus as the piston 8 moves to the position shown in Figure 2, the expander 20 rod 30 is carried with the plate 39 to cause the enlarged end 31 to expand the internal chuck segments 25.

25 The piston 8 is packed by means 51 on the rod 35, and extending toward the chuck end of the machine and formed integral with the piston there is a sleeve 52, the internal diameter of which is greater than the external diameter of the tubular member 35 to provide a recess 53. A flaring element 54 is slidably axially relative to 30 the tubular member 35 and is formed with an end 55 which moves within the recess 53. A coil spring 56 is also positioned within the recess and surrounds the tubular element 35 for normally urging the flaring element 54 toward the left 35 as viewed in Figure 2. The outer end of the flaring element 54 is formed with a cone shaped head 57 adapted to be brought into contact with the tube end 47 for flaring the same. Formation of the cone shaped head 57 on the sleeve 55 provides an annular flange 58 that is located within the counterbore 59 of the upright member 2. It will be noted that the counterbore 59 communicates with the annular recess 11, and that one face of the outer chuck 13 engages the wall 17 of 40 the counterbore. The annular flange 58 forms an abutment shoulder for the piston sleeve 52 and is adapted to be engaged by said sleeve during the deforming operation.

45 The annular flange 58 is also engageable with a pin 60 disposed in the counterbore 59 for properly locating the end of the tube with respect to the chuck 13. The pin 60 is eccentrically mounted in a sleeve member 61 having a cylindrical shaped head 62 extending above the upright member 2. The sleeve 61 is adapted to be rotated in the direction of the arrows shown in Figure 3 and since the pin 60 is eccentrically mounted therein, said pin will move forward and backward as desired with respect to the chuck 14. The sleeve 65 head 62 is yieldably held in any set position by a spring member 63 which engages notches 64 formed in the face of the enlarged sleeve end. 50 Only 180 degrees of the face is notched, since obviously 180 degrees turning of the sleeve will shift the pin 60 from its rearmost to its foremost

55

position. Rotation of the sleeve is effected through the lug 64'. After the tube has been positioned and the end thereof locked by means of the inner and outer chucks 13 and 24 respectively, movement of the piston 7 to the left will cause the end 52 to engage the annular flange 58 for forcing the conical end 57 thereof into the tube for flaring the end of the same.

The means of operating the machine is preferably hydraulic and as shown in Figure 3 of the drawings, the upright 2 is formed with a fluid passage 65 terminating at 66 within the cylinder 4 and communicating with the left hand side of the piston 7. Likewise, upright 3 has a fluid passage 67 therein terminating at 68 within the cylinder 5 and communicating with the right hand side of the piston 8. The spacer member 6 has a passage 69 terminating at 70 within the cylinder 5 and communicating with the left hand side of the piston 8. The spacer member 6 is further formed with a passage 71 to afford communication between the cylinders 4 and 5. Mounted within this passage is a ball check valve 72 backed by a coiled spring 73 removably held in said passage by means of a lock ring 74. By reason of the ball check valve 72 fluid can be exhausted from the cylinder 4 into the cylinder 5, but fluid from the cylinder 5 can only enter the cylinder 4 through the restricted passage 75.

As previously indicated, in the before-mentioned copending application, a pair of pistons are operable in individual cylinders by hydraulic means. Valves such as are well known in the art are employed for controlling the fluid, and it is to be understood that any conventional means can be employed in connection with the present invention for control of the fluid to the pistons.

In the operation of the device, let it be assumed that the pistons 7 and 8 have been moved toward each other from the position shown in Figure 2 of the drawings and are therefore in engagement with the spacer member 6. In this position the segments 20 of the chuck 13 are separated and the expander head 31 has been moved axially toward the left so that the inner chuck segments 25 are in the relaxed position shown in Figure 5 of the drawings. The tube 18 can thus be readily inserted between the inner and outer chucks and its end pushed against the cone shaped end 57 of the flaring element 54. With the piston 7 in engagement with the spacer member 6, the end 52 thereof will be out of engagement with the flaring element flange 58 so that as the tube is pushed against the flaring element, said element will move toward the right until its flange 58 engages the pin 60. Of course, prior to starting operation, the pin 60 has been properly positioned for correct location of the tube, and thus said tube when the flange engages the pin will be properly located with respect to the chuck 13. With the tube held in this position fluid from the line will enter the cylinder 5 through the passage 69 to move the piston 8 on its sleeve 43 toward the right to the position shown in Figure 2, thus moving the cam ring 12 toward the right through the draw bolts 37 causing the segments 20 of the chuck 14 to be moved radially inward into gripping contact with the tube end. Simultaneously therewith the expander rod 30 is being moved axially toward the right causing the enlarged end 31 to expand the inner chuck segments 25 outwardly and thereby expanding the tube into engagement with the outer chuck segments. It is preferred that the expander rod 30 be accurately adjusted by the means 50 so that the outer

chuck segments 20 close just an instant before the enlarged end 31 expands the inner chuck segments 25. The relative movement required to expand the tube after the outer chuck has closed is preferably accomplished by using the natural resiliency of the various parts of the machine. However, to assure greater relative movement of the expander rod after the outer chuck has closed a rubber ring 76 or similar resilient member may be interposed between the cam ring 12 and draw rods 37. As has already been noted, the internal chuck segments 25 expand the tube into engagement with the outer chuck. This is accomplished by reason of the fact that the outer chuck is first closed and then the inner chuck is moved to its full expanded position. The outer chuck therefore becomes in a large measure a sizing means for determining the external diameter of the end of the tube which is gripped by the chucks.

With the tube end thus firmly gripped by the inner and outer chucks, pressure will build up in the cylinder 5 and this fluid under pressure will travel through the passage 71 and enter the cylinder 4 through the restricted passage 75 to actuate the piston 7 toward the left carrying with it the end 52 and effecting contact thereof with the flange 58. This will move the flaring element 54 into the tightly gripped end for flaring the same as indicated at 47. After the tube end has been

deformed, a reversing valve, not shown, is actuated to cause fluid to enter the cylinder 4 through the passage 65 to move the piston 7 toward the right and exhaust fluid therefrom through the passage 71 since the check valve 72 will be moved away from its seat by the pressure of the fluid. Likewise, the piston 8 is moved toward the left by fluid entering the passage 67 and as the piston moves toward the left the fluid within the cylinder will be exhausted through the passage 69 to be returned to the reservoir. Of course, the fluid being exhausted from the cylinder 4 which passes through the check valve controlled passage 71 will also be returned to the reservoir through the spacer member passage 69.

From the above description when taken in connection with the accompanying drawings, it will be apparent that there has been provided a machine for flaring or otherwise deforming the end of a tube of a relatively large diameter. The inner and outer chucks and the manner in which they are actuated into tube gripping engagement assures that the end of the tube will be held in a very firm grip so as to prevent slipping or movement of any character during the deforming operation.

It is to be clearly understood that various changes in the details and construction and arrangement of parts may be made without departing from the scope of the invention as set forth in the claims.

I claim:

1. In a tube deforming machine, the combination of a supporting base, front and rear upright members attached to said base, a spacer member between said upright members, a cylinder on each side of said spacer member, a tubular member extending through said upright members and spacer member, pistons in said cylinders guided on said tubular member, said front upright member having an annular recess, a chuck in said recess for externally gripping the tube end to be deformed, a second chuck for internally expanding the tube end against said first chuck, means whereby said first chuck engages the tube momentarily ahead of the expansion of said second

chuck, tube end deforming means movable in said front and upright member, and means operable by said pistons to actuate said chucks and tube end deforming means.

2. In a tube deforming machine, the combination of a supporting base, front and rear upright members attached to said base, a spacer member between said upright members, a cylinder on each side of said spacer member, a tubular member extending through said upright members and spacer member, a piston in each cylinder guided on said tubular member, said front upright member being formed with an annular recess, a chuck in said recess for externally gripping the end of the tube to be deformed, a cam ring within said recess for urging said chuck into and out of tube clamping engagement, a second chuck for internally expanding said tube end against said outer chuck, means operable within said tubular member for expanding said second chuck, tube end deforming means, one of said pistons having means for causing clamping engagement of the outer chuck momentarily ahead of the expansion of said inner chuck and the other piston having means for actuating said tube end deforming means.

3. In a tube deforming machine, the combination of a supporting base, front and rear upright members attached to said base, a spacer member between said upright members, a cylinder on each side of said spacer member, a tubular member extending through said upright members and spacer member, a piston in each cylinder guided on said tubular member, said front upright member being formed with an annular recess, a chuck in said recess for externally gripping the end of the tube to be deformed, a cam ring within said recess for urging said chuck into and out of tube clamping engagement, a second chuck carried by said tubular member within said recess for internally expanding said tube end against said outer chuck, a rod slidable in said tubular member for expanding said second chuck, tube end deforming means, one of said pistons having means for causing clamping engagement of the outer chuck momentarily ahead of the expansion of said inner chuck and the other piston having means for actuating said tube end deforming means.

4. In a tube deforming machine, the combination of tube clamping means, tube deforming

means, said tube clamping means comprising an outer chuck for clamping said tube end externally and an inner chuck for expanding said tube internally against said outer chuck, a first chamber and a fluid operated piston movable therein and operatively connected with said clamping means, a second chamber and a fluid pressure operated piston movable therein and operatively connected with said deforming means, means for directing pressure fluid into the first chamber to move the piston therein for actuating the outer and inner chucks, and means for directing pressure fluid from said first chamber into the second chamber to move the piston therein for actuating said deforming means.

5. In a tube deforming machine, the combination of tube clamping means, tube deforming means, said tube clamping means comprising an outer chuck for clamping said tube end externally and an inner chuck for expanding said tube internally against said outer chuck, a first member and a fluid operated piston movable therein and operatively connected with said clamping means, a second chamber and a fluid pressure operated piston movable therein and operatively connected with said deforming means, means for directing pressure fluid into the first chamber to move the piston therein for actuating said clamping means whereby said first chuck engages the tube momentarily ahead of the expansion of said second chuck, and means for directing pressure fluid from said first chamber into the second chamber to move the piston therein for actuating said deforming means.
